UNITED STATES PATENT OFFICE.

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY.

CEMENT-KILN SYSTEM.

Application filed August 17, 1916. Serial No. 115,507.

To all whom it may concern:

Be it known that I, DAVID S. JACOBUS, a citizen of the United States, residing at Jersey City, in the county of Hudson and State of New Jersey, have invented certain new and useful Improvements in Cement-Kiln Systems, of which the following is a full, clear, and exact description, reference being had to the accompanying drawings, 10 forming part of this specification, in which—

Figure 1 is a plan view, partly in section, showing a portion of a dust-settling flue and waste-heat boiler setting for cement kilns;

Fig. 2 is a sectional side elevation of Fig. 1, showing the waste heat boiler and connections in place;

Fig. 3 is a cross section on the line III—III of the flue part of Fig. 2; 20 Fig. 4 is a detail vertical section of the connection between the kiln stack and the common flue on the plane of the line IV—IV of Fig. 1;

Fig. 5 is a sectional side elevation showing the boiler and dust recovery system which I may employ with any of the forms of dust-settling flues shown;

Fig. 6 is a partial top plan view of the dry dust catcher system of Fig. 5;

Fig. 7 is a longitudinal section showing a modified form of dust separator;

Fig. 8 is a longitudinal vertical section of a dry dust catcher and series washer and economizer which I may employ with any 35 of the boilers shown;

Fig. 9 is a sectional side elevation of the economizer of Fig. 8 showing the pipe arrangement;

Fig. 10 is a detail view of one of the spray 40 pipes for the economizer of Figs. 8 and 9;

Fig. 11 is a longitudinal section showing a modified form of series washer;

Fig. 12 is a vertical section, taken along the line XII—XII of Fig. 11;

Fig. 13 is a detail view of one of the shakers, taken along the line XIII—XIII of Fig. 14;

Fig. 14 is a plan view of the shaker taken partially along the line XIV—XIV of 50 Fig. 13;

Fig. 15 is an elevation of a modified form of shaker;

Fig. 16 is a plan view of the modified form of shaker of Fig. 15;

Fig. 17 is a detail view, partially in section, of a part of the modified form of shaker of Figs. 15 and 16;

Fig. 18 is a diagrammatic cross section showing the caking action of hot cement dust on stationary rods;

Fig. 19 is a similar view showing the caking action of hot cement dust on rotating rods;

Fig. 20 is a front elevation of a screen of 65 rotating rods;

Fig. 21 is an enlarged partial front elevation of the screen of Fig. 20;

Fig. 22 is a side view of one of the rods of Fig. 20;

Fig. 23 is a sectional elevation of a modified form of flue system;

Fig. 24 is a cross section of Fig. 23, on line XXIV—XXIV.

Fig. 25 is an elevation of one of the rod screens employed for the form of Fig. 23;

Fig. 26 is a horizontal section on the irregular line XXVI—XXVI of Fig. 23;

Fig. 27 is a horizontal section showing a modified arrangement of rotating screens;

Fig. 28 is a diagrammatic plan view showing another form of rod-holding and turning system;

Fig. 29 is an enlarged plan detail of one of the rotating elements of Fig. 28;

Fig. 30 is a sectional side elevation showing another form of dust-collecting flue and boiler system with a washer;

Fig. 31 is a plan view partly in section of Fig. 30;

Fig. 32 is a detail view of one of the screens of Fig. 30;

Fig. 33 is a cross sectional view of the form of Figs. 30 and 31, taken on line XXXIII—XXXIII of Fig. 31, looking toward the boiler;

Fig. 34 is a detail view of a double washer system which may be used instead of the single washer system;

Fig. 34^a is a detail view of a modification of Fig. 8;

Fig. 35 is a sectional side elevation showing a modified form of washers for the gases from a waste heat boiler;

Fig. 36 is a top plan view, partly broken away, of the washers of Fig. 35 showing the valve arrangement for switching from one washer to the other;

Fig. 37 is a detail view showing the con-

nections for operating the rotating shelf pieces of Fig. 35;

Fig. 38 is a detail view of one of the driving connections for giving orbital motion to a driving plate for rotating the shelf pieces of Fig. 35;

Fig. 39 is a sectional side elevation, partly on the broken line XXXIX—XXXIX of Fig. 40, showing a modified form of multiple washer system; and

Fig. 40 is a vertical section on the line XL—XL of Fig. 39.

My invention relates to the handling of dust from cement kilns. The object of the invention is to provide a method and apparatus for removing and recovering the dust which, in addition to saving the dust which is a valuable part of the material fed to the kilns, will avoid the nuisance of the settlement of dust on the surrounding grounds and buildings. It is also designed to provide for recovery of valuable products from the gases, as I have found that by suitably treating the dust-laden gases, certain valuable portions may be separated out and recovered separately from the dust proper.

The invention also relates to the reduction of the temperature of the gases, preferably by a waste heat absorbing device, prior to the final separation of the dust therefrom. The invention also relates to certain combinations and arrangements of parts hereinafter described, the advantages of which will be apparent to those skilled in the art from the following description:

Referring to the drawings, Figs. 1, 2, 3 and 4 show a form of cement kiln and flue connections which may be used with the boiler arrangement shown, or with other boiler arrangements such as those shown in the other figures; it will be understood that any of the boilers and dust recovery systems for such boilers may be used with any of the flue systems shown herein.

In Figs. 1, 2, 3 and 4 the numerals 2, 2, represent two of a series of inclined rotary cement kilns having water-cooled spouts 3 (Fig. 3), through which the cement material is fed for clinkering or sintering. The upper end of each kiln, into which the cement-forming material is fed, discharges the waste gas into the base portion 4 of an individual stack 5, this base portion having side doors 6, through which this base portion of the stack may be reached for cleaning.

Over the higher ends of the rotary cement kilns extends a common-dust settling flue 7, having hoppers 8 between the kilns. One side of this flue is connected with the cement kiln stacks through openings 9, as shown in detail in Figs. 3 and 4. These openings may be controlled by suitable closure plates or dampers (not shown) mov-

able in slots 11 (Fig. 4). When the kilns are discharging into the flue 7, the dampers in these slots are entirely removed and the slots covered by bricks or tiles *t*; and to regulate the flow of gases from the kilns to the flue and equalize the flow between the various kilns, bricks or tiles may be laid in, as shown at 12. A door 13 (Fig. 4) may be provided for introducing these bricks or tiles.

Experiments with these systems have shown that with certain grades of raw material some of the dust from the kilns will collect in caked form on hot surfaces, and that this caked material contains potash salts and other ingredients which make it valuable. It is therefore important to collect as much as possible of this caking material, as it may be sold at a much higher price than the finished cement.

In the apparatus shown in Figs. 1, 2, 3 and 4, inwardly projecting wing walls 14 are provided which cause eddies to form in the dust carrying gaseous current, which assists both in the deposition of dust in the hoppers and in the deposition of the caking material on the sides of the flue. The sides of the flue and the wing walls become heated by the gases, and the caking material adheres to such hot surfaces. Instead of the hot surfaces above described for the collection of the caking material, other forms of hot surfaces may be employed, such as the rods or screen systems shown in other figures of the drawings and hereinafter described.

The part of the dust adhering or caking to the hot surfaces has a different chemical composition from the rest of the dust which will not so adhere. It is therefore possible by means of the apparatus herein described to effect a separation of the dust having the caking characteristics from the remainder of the dust, thus recovering a valuable by-product from the cement kiln dust.

In the form of Figs. 1, 2, 3 and 4, the caking material which collects on the walls of the flue is not firmly fused to the brick-work, and but little force is required to dislodge it. To remove this collection of caked material, I may employ a cleaning device 15, attached to a chain 16, which may be lowered through any of the doors 17 in the top of the flue, these doors being adjacent to the side walls to give easy access thereto. The chain may pass over a hand windlass 18, on the top of the flue, by which the chain may be raised and lowered. In order to reach more of the wall surface, the chain may be swung from side to side by means of a bar 19, with a ring or prong at its lower end, as shown at 20, which engages the chain, this bar projecting through one of the holes in the top of the flue. With a device of this character, the sides of the flue may

be reached, except some portions near the top of the side walls, and these upper portions, as well as the roof of the flue, may be reached by curved bars passing through the doors 17. I may also use a windlass or windlassess 18^a, as shown in Fig. 2, having two chains 16^a, extending through two of the adjoining doors in the top of the flue and connected to a horizontal scraper bar 15^a, extending between and beyond the chains. These cleaning means may be used while the hot gases are passing through the flue, so that the kilns need not be shut down for such cleaning.

15 In order to clean the openings 9, between the furnace stacks and the flue, the stacks may be provided with doors 21, opposite the openings 9, and through which bars may be passed for cleaning off any deposit in the 20 openings. A cleaning device may also be dropped through this opening for cleaning off the lower part of the stack.

25 In order to segregate the valuable caking material from the dust collecting in the hoppers, I preferably first remove all the loose dust from the hopper beneath the portion of the wall to be cleaned, and then break up and remove the caked material, so that it will collect in the spouts S below the hopper 30 from which it may then be removed.

35 From the flue 7, the hot gases pass through a heat-absorbing device, which reduces their temperature before passing to the apparatus beyond, in which the final separation of the dust is effected. The heat-absorbing device is preferably one in which the waste heat is utilized, and is illustrated in the drawings as a waste heat boiler 22, connected at the end of the flue, this boiler 40 being of the general Babcock & Wilcox type with three vertical passes, beneath which are located dust hoppers 8^a, to collect the dust dropping from the gases passing through the boiler. The hoppers both for the flue and 45 boiler are also preferably provided with side doors 24, through which cleaning devices may be inserted for cleaning the hoppers when needed.

50 The waste heat boiler 22 effects a considerable reduction in the temperature of the gases, and therefore their volume, thereby reducing the velocity of the gases and permitting the dust to be more readily separated therefrom, not only during the passage of 55 the gases through the passes of the boiler, but also in the dust separator system through which the gases are afterward passed to effect the final separation of the dust. Because of the cooling of the gases, the dry dust 60 separators beyond the boiler have gases of less volume and consequently of less velocity to handle. Moreover, the washers through which the gases subsequently pass operate much more satisfactorily on the cooled gases, 65 as very hot gases tend to evaporate and

carry away the spray water in the form of steam and interfere with the satisfactory operation of the washers generally. Also, the cooled gases are much more readily handled by the fan. In cases where the final removal 70 of the dust is effected by electrical means, the reduction in temperature of the gases is of great advantage.

The non-caking dust collected in the hoppers 8^a beneath the boiler from the gases as 75 they are cooled in their passage through the boiler passes, is of a different nature from the non-caking dust collected in the flue 7, and in some instances contains enough potash to warrant its recovery from the dust. 80 The introduction of the boiler influences the character and amount of dust collected at this point.

In Figs. 5 and 6, I show one form of a 85 separator system for the gases coming from the waste heat boiler, fed from a cement kiln flue. In these figures, 25 represents a Babcock & Wilcox boiler of the cross drum type, the waste gases from the cement flue entering through the flue 26 and passing out 90 through the flue 27, to the economizer 28, and thence through flue 29 to fan 30. Some water from the boiler may be used for the economizer where the feed water supply is 95 not hot enough to prevent sweating of the 100 economizer pipes, since the dust will stick to a sweating pipe. Such water drawn from the boiler passes through a settling chamber 25', and is forced by a centrifugal pump 32 through a valved pipe 33 into pipe 34 leading to the economizer 28. A feed water heater 35 is shown for heating the feed water, before it enters the feed pump 36, by 105 which it is forced through pipes 37 and 34 into the economizer. Steam for this feed water heater 35 may be taken from the steam turbine 38, which is employed for operating the induced draft fan 30, this steam passing down to the heater 35 through pipe 39.

110 From the induced draft fan, the gases are led tangentially into the dry dust catchers or separators 40, of which I show two in series. The centrifugal force of the downwardly directed entering gaseous current, together with the change in direction, owing 115 to the outlets 41 being at the top, will cause the dust to settle in the hopper bottoms of these separators. The quality of the dust in the separators will vary, that which is farthest from the kilns containing the greater 120 amount of potash. In certain instances the potash may be recovered from the dust from some of the separators and not from others. In any case the dust which is recovered 125 is suitable for returning to the kilns by mixing it with the raw material fed to the kilns, and in reality forms the best part of the product fed to the kilns as it is in the most finely divided state.

Instead of the dry separators of Figs. 5 130

and 6, I may employ the separating system of Fig. 7, in which the gases entering from the boiler through flue 42 enter a large gravity separator 43. This separating chamber has partitions or baffles 44 and 45, which cause the gases to flow slowly up and down in an upward and downward course through the chamber. In this type of separator the reduction in volume and velocity of the gases due to their cooling in the waste heat boiler is of especial importance. The heavier particles of dust collect in the lower hoppers 46, and may be removed by conveyors 46'. The gases flow into the upper portion of a washer 47, which may be similar to the washers hereinafter more fully shown and described and which remove the finer particles of dust and certain gaseous matter.

In Figs. 8 and 9, I show a combined dry separator 48, a washing system 49 and a feed water heater or economizer 50, for the gases coming from the waste heat boiler. In this case, the dry separator 48 may be similar to one of the separators of Figs. 5 and 6, the flue 51 from its top entering the top of one member of the washing system. The washer consists of a large chamber divided by partitions 52 into a series of chambers communicating with each other alternately at the top and bottom so that the gases flow in an upward and downward course therethrough. In the last pass of this flow, the gases are acted upon by a fresh water spray from spray pipe 54, which projects into the upper part of the right hand compartment of the last chamber. The water collecting in the lower part of this last chamber is drawn out through pipe 55 to a circulating pump 56, which lifts it to the spray pipes 57 and 57'.

The pump 56 and spray pipes 57 recirculate the water through the last chamber while the spray pipe 57' sprays a portion of the water into the middle chamber, the amount being regulated by means of a valve 57'. The water dropping in the middle chamber passes out through the pipe 55^a to circulating pump 56^a, which lifts it through pipe 56^b to the spray pipes 57^b and 57^c, both spraying in the central chamber; the pipe 56^b also leads water to the pipes 57^a, which spray water in the right hand compartment of the first chamber, the amount being regulated by means of a valve 56'. The spray pipes 57^c spray water over the feed water heater, shown at 50. From the first chamber the water descends through pipe 55^b to pump 56^b which lifts it to the spray pipes 57^c, which spray water in both compartments of the first chamber. In this way the water is recirculated through both compartments of each chamber and a portion of the water from each chamber except the first passes back to the chamber in advance of it, so that the concentration of the water in each of the chambers becomes successively greater

from the last toward the first chamber. The concentrated water may be drawn off from the first chamber through the tap or valve 137.

In one of the left-hand compartments of the center chamber I locate the feed water heater or economizer 50, shown in detail in Fig. 9, and comprising alternate opposite headers 58, connected by inclined horizontal pipes 59 (Fig. 9). The circulating pump 56^b is preferably larger than the others, and lifts the water to the series of special spray pipes 57^c, which spray the water over the feed water heater tubes, thus giving a greater flow of water to prevent the material building up on the tubes of the feed water heater.

The dust from the cement kilns will become attached to tubes or pipes where there is a limited amount of moisture or water, but by providing excess of water, the tendency of the dust to attach to the tubes is greatly lessened. The feed water heater or economizer is so built that the tubes are readily accessible. The feed water preferably enters at the bottom and is taken out at the top. This feed water may be used in connection with the waste heat boiler of any of the figures.

In the bottom hopper of each double chamber of the washer I employ scraping blades 61 on hubs 61^a, each journaled in the bottom of a hopper and carrying, exterior thereof, a worm wheel meshing with a worm on shaft 62^a driven by any suitable connections. A wall of each hopper is extended and downwardly inclined to form the bottom wall 49^a of the open top trough-like structure E, so that the mud passing from the hopper and lodging in the trough, may be removed by a grab bucket 49^a, or by other means, such as a screw or drag conveyor. In Fig. 8 the normal position of structure E is shown in full lines for the first and middle chambers, and in dotted lines for the last chamber. The structure shown in full lines for the last chamber is designedly turned out of position for purposes of illustration. The concentrated solution may be drawn from the bottom of the first chamber by means of a tap or valve 137.

In Figs. 11 to 14 is illustrated another form of washing system for the gases coming from the waste heat boiler, the feed water heater or economizer being omitted. In the form shown the fresh water is fed through pipe 150 to spray 151 in the right-hand compartment of the last chamber. In this way the coldest water is sprayed into the coldest gases, and the fresh water is sprayed into the cleanest gases, as in Fig. 8.

In addition to the water sprayed through pipe 150, I also introduce water into the right-hand compartment, of the last chamber from tank 66, through pump 152, pipe 150

153 and spray 154. The water from the bottom of the last chamber passes downward through pipe 155 to pump 156, and is raised by the latter to sprays 157 in both compartments of the last chamber and also to spray 158 in the right-hand compartment of the third chamber. The amount of water passing through spray 158 is regulated by a valve 159, through means exterior of the casing. The water is recirculated through the other compartments and chambers in the same general way by the pipes, pumps and sprays shown in the drawing. The concentrated water is drawn off from the first chamber through the tap or valve 138.

In connection with this washing system is shown a system for collecting the dust washed from the gases. In this system the scraper blades 61^b are connected to chains 62^b, which are run continuously in the same direction. The material in the form of mud is removed from the bottoms of the spray chambers by means of conveyors 64^b, shown in Fig. 12. The tube 139, in which the conveyor runs, extends exteriorly to a level above the water line in the spray chambers, so that the water is not taken from the spray chambers by the action of the conveyor. The conveyors are run by sprocket wheels 63^b in the direction indicated by the arrows. The material taken by the conveyors 64^b is delivered to the tank 66. The conveyor blades as they pass above the tank are washed by means of a spray supplied from a water pipe 68, the water and washed off material falling into the tank 66. The material collecting in the bottom tank is carried along its inclined bottom by the chain and scraper system 70, and is delivered to a second conveyor 71. The conveyor 71, like the conveyor 64^b, consists of a chain carrying a number of conveyor blades and driven in the direction indicated by the arrows by sprockets 71^a. The conveyor 71 delivers the material taken from the bottom of the tank 66 onto a belt conveyor 72, traveling on an inclined pulley system over a tank 73. Shakers or strikers 139^a are arranged to dislodge the material from the conveyor 71 and cause it to fall on the belt 72. One of the strikers 139^a is shown in detail in Figs. 13 and 14, and consists of a tapper arm 140 actuated by means of a spring 141 and cam wheel 142 to strike the blades of the conveyor and knock off the wet material adhering to them.

In Figs. 15, 16 and 17 is illustrated a modified form of knocker for clearing the conveyor blades of the wet material. This form of knocker consists of a number of rods 143 hung by means of chains 144 from a circular plate 145. The plate is raised and suddenly allowed to drop by means of a cam wheel 146 engaging a roller 147 car-

ried by the plate supporting shaft 148. The rods 143 fall against the conveyor blades and chain and dislodge the material therefrom. The shaft 148 is given a slow rotary movement. The guards 149 are provided to direct the material to the middle of the belt conveyor 72 and to direct the lower ends of the rods against the conveyor blades and chain. The guards 149 also cause the rods to strike against each other and keep them clear of the muddy material.

In Figs. 18 to 22 is illustrated mechanism for collecting the valuable caking material from the dust, which has been found to be particularly effective for such purpose. The mechanism consists of rods rotatably mounted in the flue through which the heated gases from the kilns pass. The rods are preferably of iron or steel and are illustrated as hung vertical in the flue. These rods become heated by the gases to about the temperature of the gases, so as to present the hot surfaces which have been found effective for collecting the caking material. By rotating the rods they can be made to more effectively collect the caking material. If a rod is held stationary in the path of the gases, a limited amount of material will collect, the greater part of which is deposited on the opposite side of the rod from that which the current of gas strikes. This is indicated in Fig. 18, where the views show successive building up of the caking formation *a* at the side of the rod opposite that upon which the gases impinge. I have found that by turning the rod slowly the material will build up around it and the capacity of the rod for collecting the caking material is thereby greatly increased. This is illustrated in Fig. 19, in which the arrows indicate a clockwise direction of rotation or turning, and the successive cross sections illustrate the building up of the cake material *b* around the entire circumference of the rod. A distinct separation of the caking material from the remainder of the dust is assisted by the rotation of the rod, as any dust which will not cake will be blown away from the rod when the rod is revolved to a position where the gases produce a sweeping effect on that part of the rod where the dust has lodged.

In Figs. 20, 21 and 22 I have shown a screen formed of these turning rods, which I may use in any of the flues near the kilns. In this form a U-bar carrier 74 supports a series of rods 75, these rods having gear wheels 76 arranged at alternate levels so that a driving mechanism may be used for those ends of the rods projecting above the flue to rotate the portions hanging within the flue and on which the caking material collects. The lower ends of these rods are shown as having bearings in a bar 77, which holds them in spaced relation. These

screens of rotary rods when used will be hung down within the common flue of the rotary kilns, the top bearing and gears being above the slots in the top of the flue so that 5 caking portions of the dust will deposit on these turning rods.

In Figs. 23, 24, 25 and 26, I show the flue 7^a as leading from the upper end of a single rotary kiln 2^a, the water-cooled spout for 10 the cement-forming material being shown at 3^a as extending through the top of the flue between the interrupted rods of the screens. In this case, the screens 78 are formed of non-rotary rods, as shown in Fig. 15 25, and are hung through slots in the top of the flue by flexible chains or suspending devices 79, secured to each screen. These 20 flexible connections extend over suitable pulleys or sprocket wheels 80, and thence over drum 81, so that the screens may be raised and lowered, as desired. In this case, also, I show the waste heat boiler at the 25 right-hand end of the flue with the up-and-down passes for the gases, the suction fan, etc.

In Figs. 27 to 29, inclusive, I show different arrangements for the hot rods, with the individual flue system, such as shown in Fig. 23. In Fig. 27, each of the screens of 30 non-rotary rods is arranged to turn or revolve about a vertical axis; these screens being substantially the same as shown in Fig. 25 and being rotated by suitable external connections. Where rotating screens 35 of this kind are used, they produce an eddy action in the gases which assists in the deposit of caking portions of the dust. They also cause greater impingement of the gases on the hot side walls of the flue, thereby increasing the amount of material which will 40 cake on these side walls.

In Figs. 28 and 29, I show the flue as screened by groups of rods arranged in circular form on suitable upper and lower plates, 45 each group being revolved or rotated. The groups may rotate continuously in the same direction or alternately in opposite directions or in any desired order, and the individual rods may rotate as the group is 50 turned, as indicated in Fig. 29, or not, as desired.

In Figs. 30, 31, 32 and 33, I show a system generally similar to that of Fig. 23, the 55 gases from the boiler being, however, led through a washer, and the rods of the screens next to the wing walls being provided with chisel portions 75^a to aid in dislodging the caking material from the wing walls when the screens are raised and lowered. In this form, the washer system may 60 be generally similar to that shown in Fig. 11, this acting on the gases after they leave the waste heat boiler at the end of the dust flue. In this case, however, the flue is a com-

mon flue with the ports from the cement kiln 65 entering its side, as shown at 82, and the screens of rods are located between the cement kiln entrance ports, as well as in that portion of the flue between the last cement kiln and the boiler. In this case I show 70 screws 161 for conveying the dry dust from the hopper compartment of flue 7^a.

Fig. 32 shows one of the screens 79^a for this system in which the vertical rods are connected by cross rods or wires, and Fig. 75 33 shows the spout 3^b feeding the cement-forming material into the kiln. The individual stack 5^b for the cement kiln is provided with the dampers 83 and 83^a, and the port from the lower portion of the stack 80 into the flue is shown at 82. The muddy deposit is removed from the bottom of the washer by means of a chain and scraper conveyor 162 and discharged into a trough 163, from which it may be taken by any 85 suitable means. The moving conveyor plates at their dumping position may be subjected to a spray of water from pipe 164, if desired.

In Fig. 34, I show a double washer system 90 for the gases from the waste heat boiler of this improved system. From the outlet of the first washer 85, the gases flow through the outlet 86 down into the second washer 87, and finally escape therefrom to the atmosphere at 88. The water which overflows from the first washer flows through pipe 89 into tank 90, from which it flows to a second tank 91, from which it is pumped by the centrifugal pump 92 through the pipe 93 to the first washer sprays 94. Similarly, the overflow water from the second washer 87 flows through pipe 95, into tank 96, from which it is taken by centrifugal pump 97, and forced through pipe 98 to the sprays 99, for the second washer. Fresh water for the system is supplied through pipe 100, from any suitable source. A supply of water for the first washer may be taken from tank 96 either separately by pipes, or by a valved extension 101 of the pipe 98. With the series washer shown, the freshest and cleanest water is made to act on the gases after they have been partially washed, and by properly regulating the amount of water which enters the first washer, the water in the tanks 90 and 91 may be made to reach any desired degree of concentration. In this way, 110 the heat in the waste gases may be used to concentrate the wash water, with a view of recovering certain elements, such as potash, in the wash water which can be drawn off through a connection, such as shown at 102. Furthermore, by employing a series washer, 120 the elements are more cleanly washed out of the gases than by an ordinary washer, as the gases leaving the water are brought into contact with the freshest water. The mud

105

115

120

125

and slime which may accumulate in the two washers shown may be removed by conveyors or suitable devices 103.

In Fig. 34^a, I show an end view of the modification of the washer shown in Fig. 8. The inlet 51 conducts the gases into the washer, from which point they pass downward and under the partition 52 (the lower edge of the latter being indicated at 52'), 10 and then passes upward at the rear of the partition 52. The lower part of the chamber enters a tank or trough 165, formed with an inclined wall 165' and curved bottom, the tank being maintained substantially full of water by any suitable means. The precipitated solids may be removed from the bottom of the tank by means of a grab bucket 166, or by a screw or drag conveyor. A scraper or hoe 167 may be 20 employed by an operator, standing on the platform 168, to push the mud downward along the inclined wall of the tank within reach of the grab bucket, or of the conveyor.

In Figs. 35 to 38, I show the gases coming from the exhaust fan of the waste heat boiler as being fed into a pipe 104, having two branches 105, controlled by a valve or damper 106, by means of which the gas may 30 be passed through either one or both of two washers. Each flue 105 enters the lower part of one of the two washers 107, each having a water spray system 108. Within these washers are arranged horizontal rows of shelf pieces 109, on which the gas and water will impinge, and which will lead to a more thorough intermingling of the water with the gases and more complete removal of the dust and other foreign 40 elements. These shelf pieces are preferably made to turn or rotate, being carried on end shafts 110, extending through the sides of the washer and having at one end a crank arm 111. Pins 112 on the crank arms 111 enter a plate 113, which is given an orbital motion by cranks 114, through the slow motion gearing 115, shown in Fig. 38.

Each of these washers is preferably provided with a separate pump and separate tank for the wash water. In operating the washers, the water is first circulated in one of the washers until it absorbs a certain percentage of potash, etc., and reaches a certain degree of concentration. The supply of make-up water to the washer is then shut off and a circulation is maintained until a further degree of concentration is secured. While the highest concentration is being carried in one washer, the other washer will be run at a comparatively low concentration and the greater portion of the gas will be directed through the washer which is running at low concentration by adjusting the damper 106. The greater

part of the mud thrown down from the 65 gases will be removed by the conveyor 116, to which the material is fed by scrapers 117, passing over the sprocket wheels 117' and acting on the sides of the hopper-shaped bottom portion. After the solution 70 in one of the washers reaches the desired strength or concentration, it is drawn off through valve 175.

In Figs. 39 and 40 I show the gases from the waste heat boiler as being delivered 75 through flue 120 into the first of the series of spray chambers 169, each chamber being provided at its top with a division plate 121 dividing it into two compartments and communicating with the succeeding chamber 80 through an opening 122, so that the gases may be circulated in a downward and upward path through the compartments of the successive chambers until they are finally permitted to pass into the air 85 through the outlet flue 120'. Each spray chamber is formed with an inclined bottom wall 123 communicating with an open top tank 124 from which the precipitated solids 90 may be removed by means of a grab bucket 125, or by a screw or drag conveyor. A scraper 126 may be employed to scrape down mud from the inclined bottom wall 123. Each of the spray chambers is provided 95 with a separate pump 127 communicating with a pipe 128, by means of which the water at the bottom of the chamber is raised to a spray 129, the arrangement being in general the same as in Fig. 8. Thus 100 the water is circulated until it absorbs a large percentage of potash, etc., and is conveyed to the evaporating tank, which is a tower-like structure, 131, formed with an air inlet flue 132 through which air is forced from a blower or suitable apparatus, and passes upwardly through the tower and out through flue 133. Water from the spray pipe 129 for the first chamber is bypassed through valve 134 and enters the 105 evaporating tank 131 in the form of a spray from sprayer 135, and is evaporated in part by the flow of air through said evaporating tank. The unevaporated water is returned to the first spray chamber 169 110 through pipe 136. The bottom of the tank 131 may be formed similar to the corresponding portion of the spray chambers, and its inclined bottom wall may be provided with a scraper 126' driven through 115 connections with the scrapers 126 in the spray chambers. The concentrated solution may be drawn off from the evaporating tank 131 and spray chamber 169 120 through suitable valves or taps 170.

Instead of returning the unevaporated water from the evaporating tank 131 to the first spray chamber 169 it may be retained 125 in the evaporating tank 131 and recircu-

lated through the latter by means of a separate pump.

In the several washers shown, I propose to remove the potash and other foreign elements from the concentrated solution, and concentration of the solution is aided by means of the heat in the flue gases. Moreover, the air admitted into the evaporation tank, above described, may be preheated by the hot flue gases.

Where the caking material is removed from the hot gases by the means described, before they pass over a waste heat boiler, the boiler surface will be cleaner than where this material is not so removed, which constitutes a point of advantage.

Electrical means for producing precipitation of the dust may be employed in those parts of my apparatus where the dust is removed by centrifugal force or by gravity after the gases pass over a waste heat boiler, for example, electrical separators may be substituted for the centrifugal separators of Figs. 5 and 6, and for the gravity separators 43 of Fig. 7.

While different forms of apparatus have been illustrated and a number of specific applications of the method have been described, it is to be understood that the invention is not limited to the described details, but that the apparatus and method may be varied within the scope of the following claims.

What I claim and desire to secure by Letters Patent of the United States is:

1. Apparatus for treating dust-laden cement kiln gases, comprising a flue arranged to permit a current of dust-laden gases to flow substantially unobstructedly there-through without substantial change in the general direction of flow in its passage through said flue, said flue having refractory heated side walls exposed to the current of gases for the collection of a caking material, and a plurality of baffles projecting a short distance from each of said side walls at spaced intervals along the length of the flue and adapted to cause eddies in the current to bring different portions of the gases into contact with the side walls, said side walls being accessible for cleaning while the apparatus is in operation.

2. Apparatus for treating dust-laden cement kiln gases, comprising a horizontal flue having dust-collecting hoppers under it, each side wall of said flue having a plurality of vertical wings projecting into the flue for a short distance compared with the width of the flue, one or more of said wings being in proximity to each of the hoppers to assist in the deposition of dust therein.

3. Apparatus for treating dust-laden cement kiln gases, comprising a flue which contains a plurality of heated rotating rods exposed to the current of dust-laden gases

for the collection of a caking material thereon.

4. That step in the process of treating dust-laden cement kiln gases, which consists in passing them over hot surfaces and thereby separating a caking material therefrom, and recovering said caked material while continuing the operation of the kiln, the heated surfaces being arranged to be maintained at substantially the temperature of the gases.

5. The process of separating a caking material from hot dust-laden cement kiln gases, which consists in passing the gases over surfaces heated by the gases to which such material adheres, and recovering the caked material while continuing the operation of the kiln.

6. The process of separating a caking material from dust-laden cement kiln gases, which consists in passing the gases over hot surfaces to which such material adheres, and recovering the caked material while continuing the operation of the kiln.

7. That step in the process of treating dust-laden cement kiln gases, which consists in separating therefrom a caking material containing potash, and recovering the caked material while continuing the operation of the kiln.

8. The process of simultaneously separating from dust-laden cement kiln gases a non-caking dust and a caking material, which consists in passing the gases through a flue having eddy-forming obstructions and heated surfaces exposed to the gaseous current, the heated surfaces being arranged to be maintained at substantially the temperature of the gases.

9. The process of separating a caking material from dust-laden cement kiln gases, which consists in passing the gases over heated rotating surfaces to which such material adheres.

10. The process of treating dust-laden cement kiln gases, comprising passing them over heated surfaces to collect a caking material, and simultaneously allowing non-caking dust to separate therefrom, and recovering the caked material while continuing the operation of the kiln, the heated surfaces being arranged to be maintained at substantially the temperature of the gases.

11. The process of recovering a caking material from dust-laden cement kiln gases, which consists in building up a deposit of such material upon heated refractory wall surfaces exposed to the gases, and periodically cleaning the surfaces by mechanical contact devices to re-expose them, the heated surfaces being arranged to be maintained at substantially the temperature of the gases.

12. The process of treating hot dust-laden cement kiln gases, comprising the removal of a part of the dust by separating a

- caking material therefrom, recovering the caked material while continuing the operation of the kiln, and thereafter cooling the gases and subsequently precipitating a further amount of dust therefrom.
13. The process of treating hot dust-laden cement kiln gases, comprising separating a caking material therefrom by contact of the gases with hot surfaces, then passing the gases through a heat-absorbing device and thereafter separating dust from the gases.
14. An apparatus for recovering potassium compounds carried in suspension by hot gases and mixed with other solids, comprising a precipitating chamber through which the gases are caused to circulate, means for causing a precipitating liquid to come in intimate contact with said gases in said chamber, whereby a large portion of the potassium compounds and substantially all the other solids are precipitated, means for separating potassium compounds from the precipitated matter, means for conducting the gases from said chamber into a second precipitating chamber, means for causing a precipitating liquid to come in intimate contact with said gases in said second chamber, whereby substantially all the remaining potassium compounds are precipitated, and means for conveying the potassium compound containing liquid from said second chamber independently of the liquid mixture collected in the first chamber.
15. Apparatus for treating dust-laden cement kiln gases, comprising a waste heat boiler and its setting, a flue connecting the kiln and the setting and arranged to give the gases a relatively long travel from the kiln exit to the setting entrance, heated dust-collecting surfaces in said flue and adapted to be maintained at substantially the temperature of the gases contacting therewith.
16. Apparatus for treating dust-laden cement kiln gases, comprising a waste heat boiler and its setting, a flue connecting the kiln and the setting and arranged to give the gases a relatively long travel from the kiln exit to the setting entrance, heated dust-collecting surfaces in said flue and adapted to be maintained at substantially the temperature of the gases contacting therewith, and a washer through which the cooled gases pass from said heat-absorbing device.
17. A plurality of rotary cement kilns, a waste heat boiler, a flue into which the individual kilns open at points at varying distances from the boiler and which connects the series of kilns to the waste heat boiler, a draft-producing means to create a draft through the kilns, the flue and the boiler, the connection between each kiln and the flue being arranged to equalize the flow of gases through the several kilns irrespective of their relative distances from the draft-producing means and while maintaining the desired velocity of the gases through the boiler, and dust-collecting chambers between the cement kilns and the openings therefrom to the common flue, in which chambers some of the dust in the kiln gases is collected, the gases thereafter flowing through the openings into the common flue.
18. In testimony whereof, I have hereunto signed my name in the presence of two subscribing witnesses.
- DAVID S. JACOBUS.
